UNITED STATES PATENT OFFICE.

WALTER J. HERSCHEDE AND CHARLES COHAN, OF CINCINNATI, OHIO, ASSIGNORS TO THE HERSCHEDE HALL CLOCK COMPANY, OF CINCINNATI, OHIO, A CORPORATION OF OHIO.

CHIME-STRIKING HAMMER.

1,250,172.

Specification of Letters Patent. Patented Dec. 18, 1917.

Application filed November 11, 1916. Serial No. 130,697.

To all whom it may concern:

Be it known that we, WALTER J. HERSCHEDE and CHARLES COHAN, citizens of the United States of America, and residents of 5 Cincinnati, in the county of Hamilton and State of Ohio, have invented a new and useful Improvement in Chime-Striking Hammers, of which the following is a specification.

The invention relates to improvements in 10 chime striking hammers for chime clocks and particularly to the hammer head mounting means.

In ordinary chime striking hammers, the means for mounting the hammer head consists of a flat strip of spring metal which is secured at one end to the hammer head and at its opposite end to a rigid support, the spring being held in a vertical position. This spring is provided at a point slightly below 15 the hammer head, with a means for retracting the spring for the purpose of giving the hammer the desired impulse for the blow, the means usually consisting of a cord attached directly to the spring at this point and extending to the hammer operating 20 mechanism. The objection encountered in using this ordinary chime striking hammer has been that when the hammer head is located slightly too close to the chime tube 25 which it is to strike, the tendency is for the hammer head to rebound after having struck the tube its initial blow, and to give the tube a second and possibly a third blow. This multiple striking of the chime tube results 30 in confusing and discordant sounds during the ringing of the chime. In order to overcome this objection it is found necessary to readjust the cord connecting the hammer with its operating mechanism, in order to 35 increase the distance of the hammer from its chime tube and to thereby prevent the rebound movement of the hammer head from striking the tube a second blow. The reason 40 for this rebounding of the hammer head is that when the hammer has been released 45 after having been retracted previous to striking its blow, the movement of the hammer toward the chime tube is suddenly restricted because of the cord having been drawn taut 50 and thus causing the portion of the hammer spring between the point to which the cord is attached and the hammer head to bend, the suddenness of this movement causing this short length of spring to vibrate the

hammer head vigorously, giving the head a 55 series of sharp tube-striking movements.

It is to overcome this serious objection to ordinary chime striking hammers, that we have devised the chime striking hammer herein illustrated and described, in which 60 an object is to produce a chime striking hammer which will absorb any rebounding movements of the hammer head, after having been given its initial striking movement.

A further object is to produce a chime 65 striking hammer in which the intensity of blow given the chime tube by the hammer, will not be materially varied upon slight changes of position of the hammer head with relation to the chime tube. 70

A further object is to produce a chime 75 striking hammer which will eliminate the necessity of extreme accuracy in the adjustment of the position of the hammer head with relation to the chime tube.

These and other objects are attained in the chime striking hammer described in the following specification and illustrated in the accompanying drawings, in which;

Figure 1 is a fragmental elevational view 80 of a chime striking hammer in its normal or inoperative position, the hammer head being shown in dotted lines in its chime striking position.

Fig. 2 is a view similar to Fig. 1, but showing the hammer in its retracted position, ready to be released for the purpose of striking the chime tube. 85

Fig. 3 is a fragmental perspective view of the hammer embodying our invention. 90

The hammer illustrated in the accompanying drawings, consists of the usual hammer head 4 which is mounted at the upper end of a vertically positioned flat spring 5, the lower end of which is secured in a suitable 95 support 6. Adjacent to the upper end of the spring 5 a relatively narrow strip 7 is punched from the flat spring 5, the strip being punched from the central portion of the spring and having its upper end severed therefrom, with its lower end bent outward 100 to hold the strip in spaced relation to the body of the spring, as disclosed in Figs. 1 and 3. This position of the strip with relation to the body of the spring, permits the strip to act independently of the spring. In other words, it permits of the strip acting as 105 a spring auxiliary to the main spring 5. At

the upper end of this strip 7 an aperture is provided, the aperture permitting of the passage therethrough of the end of the cord 8 which extends to the operating mechanism 5 of the hammer, the end of the cord being provided with a knot 10 as is usual in fastening cords to chime striking hammers.

In operating a chime striking hammer embodying our invention as above described, 10 the hammer operating mechanism 9 is pulled back to the position disclosed in Fig. 2, during which movement the hammer spring 5 is retracted from its normal position as disclosed in Fig. 1, and the strip 7 is moved 15 from the normal position disclosed in Fig. 1 to the angular position disclosed in Fig. 2, the strip 7 being bent slightly during such movement with relation to the spring 5. This causes the hammer head 4 to be moved 20 to such a position that when the mechanism 9 releases the spring 5, the hammer head will be caused to rapidly approach and strike the chime tube, the striking of the tube taking place in the following described manner. 25 As soon as the spring 5 is released, it is permitted to assume its normal position as disclosed in full lines in Fig. 1, the strip 7 also assuming its normal position. However the inertia of the hammer head after 30 having been brought to its normal position, causes it to continue in its line of movement until the padded end thereof is brought into engagement with the chime tube, this continued movement causing the spring 5 to 35 flex above the point at which the strip 7 connects with the spring as disclosed in dotted lines in Fig. 1. During this flexing movement the strip 7 maintains its normal position, the flexing of the spring 5 above the 40 point of connection of the strip 7 therewith, causing the strip 7 to occupy an angular position with relation to the upper end of the spring. Such a movement of the upper end 45 of the spring is now absorbed by the flexing of the strip and upper portion with relation to one another, so that the force of the rebound of the upper portion, after the hammer head has struck the tube, is absorbed by the strip 7 which acts as an auxiliary 50 spring adapted to absorb the rebounding movement of the main spring 5. Thus the upper end of the main spring has all of its tendencies toward rebounding movement,

dampened and absorbed. Thus the hammer is caused to give but one sharp and distinct 55 blow upon the chime tube.

In ordinary chime hammer constructions this is not true, because in such constructions there is positively nothing which absorbs the rebounding movement of the upper end of the main spring and the hammer head attached thereto. 60

Having thus described our invention, what we claim is;

1. A chime striking hammer comprising 65 a hammer head, a mounting spring adapted to have the hammer head attached thereto at one end and to be fixed against movement at its opposite end, and an auxiliary spring attached at one end to the first mentioned 70 spring and adapted to have its opposite end operatively connected with a chime operating mechanism.

2. A chime striking hammer comprising 75 a hammer head, a mounting spring for the hammer head, and an auxiliary spring secured at one end to the mounting spring adjacent to the hammer head, and having its opposite end adapted to be operatively connected with a hammer operating mechanism. 80

3. A chime striking hammer comprising a flat leaf spring, a hammer head attached to one end thereof, and an auxiliary flat leaf 85 spring attached at one end to the first mentioned spring and having its free end extending toward the hammer head, said free end being adapted to be operatively connected to a hammer operating mechanism.

4. A clock hammer comprising a hammer 90 head, and a flat spring upon one end of which the hammer is mounted, the flat spring having a narrow strip struck from it adjacent to the hammer, the end of the narrow strip remote from the hammer head being 95 integral with the flat spring and the opposite end thereof being adapted to be connected to the operating mechanism.

In testimony whereof, we have hereunto subscribed our names this 3rd day of 100 November, 1916.

WALTER J. HERSCHEDE.
